APPARATUS AND PROCESS FOR FEEDING SLURRY

Walter C. Davis, Haverford Township, Delaware County, Pa., assignor to The Sharples Corporation, a corporation of Delaware

Application May 16, 1946, Serial No. 670,243

9 Claims. (Cl. 210—68)

1. A apparatus for feeding

The present invention is concerned with an apparatus for intermittently feeding a slurry of solids and liquid and more particularly to an apparatus and process for feeding a machine designed to dehydrate and discharge the solids. While the features of the invention may be employed in feeding slurries to machines of varying design, the invention can perhaps best be illustrated by consideration of its application to the feed of slurries for treatment in the machine of the patent to Brewer, 2,271,493, as the invention was conceived as an arrangement for effecting feed of slurry to a machine of this type.

In the Brewer patent, slurry is fed from a source of feed through a conduit to a centrifugal rotor in which dehydration takes place, and the feed of the slurry to the machine is controlled by a valve. The machine operates on a timed cycle including a sequence of feeding, rinsing and discharging operations, and the feed of slurry to the machine is continued only during a part of this cycle. As illustrated in the Brewer patent, the opening and closing of the slurry-feed control valve is accomplished by fluid pressure and spring means.

In the feeding of solids to a machine such as illustrated in the Brewer patent, a mixture of liquid and solids is ordinarily passed to a tank which constitutes a source of feed to the centrifugal rotor, and the slurry is fed from this source through the above-mentioned conduit and feed valve to said rotor. Difficulty is sometimes encountered in obtaining free flow of the slurry from the source of feed to the centrifugal, particularly after the feed valve has been closed for a time and solids have had opportunity to settle and pack in the conduit, and a feature of the present invention consists in the fact that it provides an arrangement for facilitating such flow, while at the same time minimizing the problem created by passage of an excess of liquid to the centrifugal rotor. In the practice of the present invention, a special liquid feed line is provided which empties into the conduit through which the slurry flows to the centrifugal at a point between the source of feed of such slurry and the slurry-feed control valve, and this supplemental feed of liquid is controlled in such a way that liquid flows into and upward through the slurry-feed conduit only at such times as the main slurry-feed control valve may be closed. Thus, upward flow of liquid prevents the settling and packing of solids in the feed conduit and the entrance to it.

The detailed nature of the invention, and fur-

ther details of the apparatus and process will be set forth in the following description of the accompanying drawing of the apparatus and process, and the following claims will set forth the scope of the invention.

APPARATUS AND PROCESS FOR FEEDING SLURRY

Walter C. Davis, Haverford Township, Delaware County, Pa., assignor to The Sharples Corporation, a corporation of Delaware

Application May 16, 1946, Serial No. 670,243

9 Claims. (Cl. 210—68)

1. A apparatus for feeding

ther features and advantages will be evident from a reading of the following specification in the light of the attached drawing, in which,

Figure 1 is a flow sheet illustrating the feed of slurry and supplemental liquid in practice of the invention,

Figure 2 is a side elevation illustrating control of the slurry-feed and supplemental liquid-feed valves,

Figure 3 is a cross section, partly in elevation, illustrating the detailed control of the slurry-feed valve, and

Figure 4 is a view similar to Figure 3, illustrating control of the supplemental liquid-feed valve.

Referring to Figure 1 of the drawing, the slurry comprising solids and liquid to be subjected to centrifugation may be fed through conduit 10 to a source of feed consisting of a feed tank 11, which also acts as a settling tank, and which is provided with a conduit 12 for decanting off excess liquid. The thickened slurry flows from tank 11 through conduit 13 to the centrifugal 14, dehydrated solids being discharged from the centrifugal at 15 and removed liquid separately discharged at 16. A valve 17 permits intermittent feed of slurry to the centrifugal, which is of the periodic type as distinguished from a continuous type.

In order to assist in the flow of solids to the centrifugal, there is provided a liquid feed conduit 19 through which supplemental liquid (e. g., mother liquor of crystals under treatment) may be discharged into the conduit 13 at a point 20 between the tank 11 and valve 17. While this supplemental liquid serves to avoid concentration and packing of the solids in the feed line and thus assists materially in facilitating free flow of the slurry to the centrifugal, it is undesirable that an excessive quantity of liquid be fed to the centrifugal since the rate at which solids may be fed to the centrifugal depends largely upon the amount of liquid fed therewith which must be separated from the solids during the feeding cycle. This excess liquid must filter through the cake of crystals being built on the screen, and then through the screen, and the rate of passage is limited and controls the rate at which the slurry may be fed.

In the practice of the present invention, there is provided an apparatus and process by which the feed of supplemental liquid to a portion of the conduit 13 between the tank 11 and valve 17 occurs only during the part of the cycle of operation when the valve 17 is in closed position, and thus prevents flow of slurry to the centrifugal.

The feed of supplemental liquid through conduit 19 to the point 20 is controlled by valve 18, and this valve 18 is maintained in open position when the valve 17 is in closed position, and vice versa. By this arrangement, supplemental liquid flows into the conduit 13 at the point 20 at such times as the solids cannot pass on through the conduit 13 due to the closing of the valve 17, but flow of supplemental liquid into the conduit 13 is suspended just as soon as the valve 17 is opened to permit feed of slurry to the centrifugal. The feed of additional liquid beyond that flowing through the conduit 13 from tank 11 is thus prevented during the normal slurry feeding portion of the cycle of operations, with the result that the centrifugal operation is not burdened by the necessity of removal of additional liquid introduced at 20 during this portion of the cycle. The feed of supplemental liquid is accomplished only during the portion of the cycle when such feed is most useful in maintaining the solids in the conduit 13 in a fluid condition, to wit, during the time when the feed to the centrifuge is shut off. In the practice of the invention, the valves 17 and 18 may be intercontrolled in the desired manner by use of a three-way valve to effect control in both the slurry-feed conduit and the liquid-feed conduit, or these valves may be operated by the same or separate motors.

Figures 2 to 4 of the drawing illustrate a preferred means for accomplishing control of the valves 17 and 18. As illustrated in these figures, fluid pressure from conduit 21 serves to actuate fluid pressure motor 22 controlling valve 18 in conduit 19 and also to actuate fluid pressure motor 23 controlling valve 17 in conduit 13.

As illustrated in Figures 3 and 4, the fluid pressure motor 22 causes closure of the valve 18 against the pressure of spring 24 when fluid under pressure is admitted to motor 22. This motor may, for example, be of the familiar diaphragm type and operated by compressed air admitted through conduit 21. Valve 17 is caused to move to open or flow-permitting position upon admission of fluid under pressure to the motor 23, which may be of the same type as the motor 22, while spring 25 causes closure of this valve upon release of the compressed air or other actuating fluid from the conduit 21. It will be seen that, when the actuating fluid is admitted under pressure into conduit 21, the valve 17 will be opened in opposition to the force exerted by the spring 25 and the valve 18 closed in opposition to the force exerted by the spring 24. Thus, when fluid under pressure is admitted to conduit 21, the slurry-feed valve 17 will be opened and the supplemental liquid-feed valve 18 will be closed, while upon release of this pressure, the slurry-feed valve 17 will be closed and the supplemental liquid-feed valve 18 will be opened.

Various modifications are available within the scope of the invention, and I do not therefore wish to be limited except by the scope of the following claims.

I claim:

1. In an apparatus for feeding a slurry of solids and liquid intermittently to a machine for separating liquid from said solids, the combination comprising a settling tank, a slurry-feed conduit extending from the lower portion of said settling tank to said machine, a slurry-feed valve in said slurry-feed conduit, a liquid-feed conduit interconnected with said slurry-feed conduit at a point upstream from said slurry-feed valve, said liquid-feed conduit being designed to feed liquid into

said slurry-feed conduit in a direction opposed to the direction of normal flow in said slurry-feed conduit, a liquid-feed valve in said liquid-feed conduit positioned to control feed of liquid from said liquid-feed conduit into said slurry-feed conduit, and a motor for actuating said liquid-feed valve to flow-permitting position when said slurry-feed valve is in flow-preventing position and to flow-preventing position when said slurry-feed valve is in flow-permitting position.

2. Apparatus as defined in claim 1 in which a like motor is employed to actuate said slurry-feed valve.

3. In an apparatus for feeding a slurry of solids and liquid intermittently to a machine for separating liquid from said solids, the combination comprising a settling tank, a slurry-feed conduit extending from the lower portion of said settling tank to said machine, a slurry-feed valve in said slurry-feed conduit, a liquid feed conduit interconnected with said slurry-feed conduit at a point upstream from said slurry-feed valve, said liquid-feed conduit being designed to feed liquid into said slurry-feed conduit in a direction opposed to the direction of normal flow in said slurry-feed conduit, a liquid-feed valve in said liquid-feed conduit positioned to control feed of liquid from said liquid-feed conduit into said slurry-feed conduit, and fluid pressure means for actuating said liquid-feed valve to flow-permitting position when said slurry-feed valve is in flow-preventing position and to flow-preventing position when said slurry-feed valve is in flow-permitting position.

4. Apparatus as defined in claim 3 in which the fluid pressure system including said fluid pressure means serves also to actuate said slurry-feed valve.

5. In an apparatus for feeding a slurry of solids and liquid intermittently to a machine for separating liquid from said solids, the combination comprising a settling tank, a slurry-feed conduit extending from the lower portion of said settling tank to said machine, a slurry-feed valve in said slurry-feed conduit, a liquid feed conduit interconnected with said slurry-feed conduit at a point upstream from said slurry-feed valve, said liquid-feed conduit being designed to feed liquid into said slurry-feed conduit in a direction opposed to the direction of normal flow in said slurry-feed conduit, a liquid-feed valve in said liquid-feed conduit positioned to control feed of liquid from said liquid-feed conduit into said slurry-feed conduit, and pneumatic means for actuating said liquid-feed valve to flow-permitting position when said slurry-feed valve is in flow-preventing position, and to flow-preventing position when said slurry-feed valve is in flow-permitting position.

6. Apparatus as defined in claim 5 in which the pneumatic system including said pneumatic means serves also to actuate said slurry-feed valve.

7. A process for intermittently feeding a slurry of solids and liquid to a machine, comprising the steps of establishing a flow of slurry in a feed line to said machine, intermittently interrupting said flow of slurry in said feed line, and, in the course of such interruptions, establishing a reverse flow of a small amount of supplemental liquid in said feed line sufficient to inhibit settling and packing of solids in said feed line.

8. The process of feeding a slurry of solids and liquid from a feed tank to a machine for separating liquid from said solids, comprising the steps

of establishing a normal flow of slurry in the feed line to said machine, periodically interrupting said normal flow of slurry, and, in the course of said interruptions, introducing a small amount of supplemental liquid into said feed line sufficient to inhibit settling and packing of solids in said feed line, the introduction of said supplemental liquid into said feed line being in a direction opposed to the direction of normal flow of slurry in said feed line.

9. In an apparatus for feeding a slurry of solids and liquid intermittently, the combination comprising a slurry-feed conduit, means for supplying slurry to said slurry-feed conduit, a slurry-feed valve in said slurry-feed conduit, a liquid-feed conduit interconnected with said slurry-feed conduit at a point upstream from said slurry-feed valve, said liquid-feed conduit being designed to feed liquid into said slurry-feed conduit, a liquid-feed valve in said liquid-feed conduit posi-

tioned to control feed of liquid from said liquid-feed conduit into said slurry-feed conduit, and means for actuating said liquid-feed valve to flow-permitting position when said slurry-feed valve is in flow-preventing position, and to flow-preventing position when said slurry-feed valve is in flow-permitting position.
